poration of Wisconsin

Application March 30, 1943, Serial No. 481,124

2 Claims. (Cl. 206—57)

This invention relates to a carton for holding a stack of interfolded sheets, the carton being provided with means for dispensing one sheet at a time from the carton while retaining the remainder of the stack of sheets in the carton.

In previous constructions difficulty has been encountered during the dispensing of individual sheets from the carton because the interfolded sheet succeeding the foremost sheet withdrawn has a tendency to cling to the foremost sheet causing removal of more than one sheet at a time. According to the present invention, this difficulty has been overcome by providing a pair of opposed resiliently hinged flaps bordering on the dispensing opening which resiliently engage the individual sheets as they are withdrawn and retain the sheet succeeding the foremost sheet from being withdrawn when the foremost sheet is dispensed.

Further advantages and details of the invention will be apparent from the following specification and drawing wherein.

Figure 1 is a perspective view of the dispensing carton embodying the features of the present invention.

Figure 2 is a similar view showing the tear-out strip removed for permitting dispensing individual sheets contained within the carton.

Figure 3 is a sectional view taken on lines 3—3 of Figure 2.

Figure 4 is a sectional view taken on lines 4—4 of Figure 2.

Figure 5 is a plan view of the blank from which the carton of Figure 1 is made, and

Figure 6 is a fragmental perspective view of the carton showing the first step in removing the tear-out strip.

Referring more particularly to the drawing, the carton is formed from a single blank of suitable sheet material, such as cardboard and the like, suitably cut and scored as shown in Figure 5 to provide rear panel 10, bottom panel 11, front panel (consisting of panel portions 12, 13 and 14), top panel 15, extension panel 16 and glue panel 47. End flaps 17, 17', 18, 19, 19' and 20 are hingedly connected to the rear, bottom, front and top panels, respectively, to provide end closures for the carton. The front panel is provided with top and bottom score lines 28 to form an upper panel portion 14 and lower panel portion 12.

The intermediate front panel portion 13 is adapted to be removed to provide a dispensing opening. For this purpose the intermediate panel portion is provided with two opposed ar-

cuate-shaped tearing lines which are continuously slit or cut at each end 26 for a substantial distance inwardly and are continued as a series of spaced cut scores or perforations 25 intermediate the slit end portions. Continuous cut score lines 29 are also provided which intersect the cut score lines 26 at right angles thereto at each of the ends of the intermediate front panel portion as shown in Figure 5 and extend to the score lines 28. The cut score lines 29 are joined by a series of spaced perforations indicated by numeral 27. The score lines described form an integral elongated substantially oval-shaped tear-out strip 13 which is adapted to be torn out when the carton is used to form a dispensing opening extending the full width of the front wall, preferably at its intermediate portion. The corner portions 31 of the intermediate front panel are adapted to be depressed since they are disconnected from the panel by cut slits 26 and 31.

If desired, the rear panel 10 may also be formed with similar scores as on the front panel for providing a second dispensing opening for the carton. The top panel 15 has hingedly connected thereto an extension panel 16, to which in turn is hingedly connected a glue panel 47. The glue panel is adapted to be folded back on panel 16 to provide a grasping portion in the event it is desired to open the carton for removing the entire stack of sheets therein through the top.

In forming the carton from the blank shown in Figure 1, glue panel 47 is first folded over on the inner face of extension panel 16 and glued thereto. Rear panel 10 is then folded over on the blank so as to overlap panel 13. Top panel 15 is then folded over to overlap panel 13 and glue panel 47 is adhered to the overlapped outer marginal portion of panel 10 in the relation shown in Figures 1 and 4.

One end of the carton is then formed by folding flaps 18 and 20 in opposed relation at right angles to their adjacent panels. Flap 17' is then folded over into contact with flaps 18 and 20. Flap 19 is then folded over and adhered to flap 17'. A stack of interfolded sheets 50 is then placed in the carton through the open end and the flaps 18 and 20 are folded over the adjacent end of the stack of sheets. Flaps 19 and 20 are then folded over in sequence, flap 20 being adhered to flap 17, thereby completely sealing the carton, as shown in Figure 1.

In using the carton for dispensing single sheets, a pair of corner portions 31 at one end of the front panel are depressed by the fingers, as shown.

in Figure 6, whereby it is possible to grasp the cut free edges of the tear-out strip 13 formed by the cut slits 28. The end of the tear-out strip is then torn out first along the perforated line 27, then along the opposed pair of perforated lines 28, and finally along perforated line 27 at the other end of the front panel. A dispensing opening is thereby provided in the intermediate front panel of the carton as shown in Figure 2, extending the full length of the panel.

The foremost sheet A of a stack of interfolded sheets 50 may then be removed from the carton without disturbing the remaining sheets retained in the carton. After the integral tear-out strip 13 is removed it will be noted in Figure 2 that an upper flap portion 60 and a lower flap portion 61 are provided which are resiliently hinged along score lines 29 to the upper and lower panel portions, respectively of the front panel. The free exposed edges of the flaps 60 and 61 extend short of each other when fully extended as shown in Figure 2.

These opposed resiliently hinged flaps thus border on the opposed upper and lower marginal edges of the dispensing opening and resiliently engage the individual sheets A as they are withdrawn. Hinged flaps 60 and 61 have opposed arcuate-shaped free edges and serve to frictionally engage and hold back the sheet succeeding the foremost sheet A when the latter is withdrawn through the dispensing opening. The flaps are adapted to hinge outwardly along score line 28 when the foremost sheet is withdrawn since they are disconnected at their ends by cut slits 29 and when tension on the outwardly hinged flap is relieved upon complete removal of the foremost sheet, the flaps will tend to resiliently spring back toward the front panel and engage the next succeeding sheet within the carton. This construction very effectively prevents withdrawal of more than one sheet at a time through the dispensing opening, particularly when a stack of interfolded slippery sheets of waxed paper is packaged in the carton.

Changes may be made in the arrangement of parts and construction of the carton without departing from the spirit of the invention, the scope of which should therefore be determined by reference to the appended claims.

We claim:

1. A carton for holding and dispensing a stack of interfolded sheets having a front, rear, bottom and side panels, said front panel being provided with opposed arcuate-shaped lines of tearing which define an elongated oval-shaped integral removable tear-out portion adapted to be torn out of said front panel to form a dispensing opening extending for the full width of said front panel, the ends of said arcuate-shaped lines being cut for a substantial length to facilitate initial tearing of said tear-out portion, score lines provided in said front panel to form flaps resiliently hinged at the opposed upper and lower 15 marginal edges of said dispensing opening and having the free exposed edges of said flaps extending short of each other, said flaps adapted to resiliently engage the foremost individual sheet of the stack when withdrawn through the dispensing opening and hold back the next succeeding sheet.

2. A carton for holding and dispensing a stack of interfolded sheets having a front, rear, bottom and side panels, said front panel being provided with opposed arcuate-shaped lines of tearing which define an elongated integral removable oval-shaped tear-out portion adapted to be torn out of said front panel to form a dispensing opening extending for the full width of said front 25 panel, the ends of said arcuate-shaped lines being cut inwardly for a substantial length, cut score lines intersecting the ends of said lines of tearing to form compressible portions in said front panel adjacent the ends of said tear-out portion 30 to permit grasping the ends of the tear-out portion, parallel score lines provided in said front panel spaced from said arcuate-shaped lines of tearing and extending the full width of said front panel to form flaps resiliently hinged at the opposed upper and lower marginal edges of said dispensing opening and having the free exposed 35 edges of said flaps extending short of each other, said flaps adapted to resiliently engage the foremost sheet of the stack when withdrawn through the dispensing opening and hold back the next succeeding sheet within the carton.
